UNITED STATES PATENT OFFICE.

HOWARD G. KING, OF DENVER, COLORADO.

ORE-DRESSING MACHINE.

971,046.

Specification of Letters Patent. Patented Sept. 27, 1910.

Application filed August 30, 1909. Serial No. 515,249.

To all whom it may concern:

Be it known that I, HOWARD G. KING, a citizen of the United States of America, residing in the city and county of Denver and 5 State of Colorado, have invented a new and useful Ore-Dressing Machine, of which the following is a specification.

My invention relates to improvements in ore dressing machinery, and the objects of 10 my invention are: First, to provide an ore feeding, crushing, pulverizing, and screening mill. Second, to provide a grinding mill in which the ore or other material to be crushed and pulverized is fed in a rotative 15 path continuously onto the tread rings in front of the crushing and pulverizing rolls. And third, to provide a grinding mill in which the weight of the hopper and feed mechanism is added to the weight of the 20 crushing rolls to increase their pressure against the material being crushed. I attain these objects by the mechanism illustrated in the accompanying drawings, in which:

25 Figure 1, is an end elevation of the improved ore dressing machine. Fig. 2, is a vertical, longitudinal sectional view of the same, on the line 2—2 of Fig. 1. Fig. 3, is a vertical sectional view showing the two-part circular base, which supports the tread ring, the revoluble distributing receptacle and the crushing rollers. Fig. 4, is a plan view of the two-part base. Fig. 5, is a side view thereof. Fig. 6, is a plan view of the 30 two-part casing around which the tread ring is placed. Fig. 7, is a plan view of a portion of the two-part tread ring, showing the manner of connecting the parts. Fig. 8, is a sectional view through one of the crushing 35 roller bearings. And Fig. 9, is a bottom view of the conical feed plate.

Similar letters of reference refer to similar parts throughout the several views.

Referring to the accompanying drawings, 40 the numeral 1, indicates the base, which is in the form of a two part, inverted, conical ring, the meeting edges of which are formed with apertured lugs 2, which receive securing bolts 3, by which the two members are 45 secured together. A platform 4, of less diameter than the upper edge of the base, is integrally connected thereto by a depending rim 5, which is formed with a plurality of 50 apertures 6, which permit ore or other material to pass down and over the lower edge of the base, and into a screen, as will fully ap-

pear hereinafter. The platform 4, is on a level with the upper edge of the base, and is divided centrally the same as the said base. The base is supported upon legs 7, which are 60 bolted to a two-part foundation plate 8.

A circular housing 9 of suitable height, is secured to the upper portion of the base, and four uprights 10, are secured to the base and to the housing, and extend up a suitable distance above the housing. These uprights are arranged in opposite pairs, and each pair are connected at their upper ends by metal strips 11, while each two oppositely positioned uprights are connected at their 70 upper ends by angle bars 12, and between said angle bars and the housing, by angle bars 13 and 14. These uprights and angle bars form a supporting structure, which is braced by bars 15, which diverge from the 75 upper corners of the structure, and are secured at their lower ends to the base.

Upon the platform 4, is supported a two-part cap or casing 16, having a central hub 17. This cap is of less diameter than the 80 platform, and around the peripheral edge of the same is placed a ring 18, and around the ring 18 a two-part tread ring 19, which rests upon the platform, and is flush with its peripheral edge. This tread ring is composed of two half sections, the meeting edges of which are provided with apertured lugs 20 (see Fig. 7), through which securing bolts 21 pass. The parts of the cap 16 are provided with apertured lugs 22, which receive 85 securing bolts 23. A pair of crushing rollers 24, are adapted to travel upon the tread ring 19, and these rollers are formed with integral hubs 24^A, which are adapted to turn in bores 26, formed in journal bearings 25, which are bolted to the bottom of a revoluble ore receptacle, as will be presently 90 shown. The hubs 24^A are formed with oil apertures 27, which extend through to the bore of the hub, and the bores 26 of the journal bearings 25, terminate in bores 28, which 95 are in line with and of the same diameter as the bore of the hubs 24^A, and through the rollers and their hubs 24^A and the bores 28 100 of the journal bearings 25, extend short hollow shafts 29, the inner ends of which are secured in the opposite ends of a cross 30. The journal bearings are made fast to the shafts 29 by set screws, as shown in Fig. 8, 105 and upon the outer end of the shafts are screwed caps 29^A, which enter circular depressions or recesses 29^B in the outer faces 110

of the rollers, and these caps are prevented from working off the shafts by pins 29^c, which extend through the caps and end of the shafts. The shafts 29 are provided with 5 oil apertures 29^d, which communicate with the axial passages 29^e in the shafts, so that oil may flow through the shafts and work out through the apertures 29^d to the bores of the roller hubs, and thence through the 10 apertures 27 to the bores 26 of the bearings 25, and the oil is supplied in a manner to be presently shown. The rollers turn upon the shafts 29, and their hubs 24^a turn within the bores 26 of the bearings 25, and the rollers 15 are retained upon the shafts by the caps 29^a. The outer ends of the bearings extend into recesses 29^f in the inner faces of the wheel, and this construction presents an effective means of preventing the entrance of dust 20 or grit to the interior of the bearings.

A hollow shaft 31, extends from the upper end of the cross to the top of the machine, and a hollow shaft 32, extends from the lower end of the cross down through the 25 hub 17 of the cap 16, and through a bearing 33, mounted in a central aperture of the platform 4. The lower end of the shaft 32, is plugged as shown at 32^a, Fig. 3, and an oil aperture 34 is formed in the shaft so as 30 to communicate with the bearing 33. A coupler 35, is screwed upon the lower end of the shaft 32, and a shaft 36 is screwed therein, and extends down a suitable distance below the base, and a spider 37 is 35 bolted upon its lower end. A wheel 38 is secured by a set screw to the shaft 36, a slight distance below the lower end of the base, and this wheel is preferably an ordinary cast iron band wheel of slightly greater 40 diameter than the lower end of the base, and against the lower end of its hub is secured by bolts 38^a a sheet metal disk 39, of less diameter than the wheel, so as to leave an annular space between its peripheral edge 45 and the rim of the wheel. Around the wheel is secured the upper end of an inverted conical screen 40, by means of a metal band 41, which clamps the screen upon the wheel, and this band may be secured against 50 displacement by bolts which pass through the band and through the rim of the wheel. The screen is secured about midway of its length to the spider 37, and in its lower end, which is formed with a discharge opening, 55 is secured a short section of pipe 41^a, which extends loosely into a discharge spout 42. A conical chute 43 surrounds the screen, and lies parallel with it, but is enough larger than the screen to leave a space of suitable 60 width between it and the screen, for the passage of the screened material, as will presently be shown.

Upon the lower end of the chute is secured 65 a spout 44, which receives and discharges the material from the chute. The spout 42

passes through the spout 44, so that the coarse and fine materials are kept separate from each other, and is secured to the chute in any preferred way. Upon the upper end of the shaft 31, is screwed an oil cup 45, 70 which supplies oil through the shaft 31, cross 30, and shafts 29, to the journal bearings 25, as above described, and through the shaft 32 and aperture 34 to the bearing 33. Upon the journals 25 is secured a cylindrical 75 ore receptacle 46, through the axial center of which passes the shaft 31, and from opposite sides of the bottom of this receptacle depending distributing pipes 47 extend to within a slight distance of the tread ring 19. 80 Shield plates 48, which are semi-circular in cross section, are secured at their upper ends to the receptacle 46, and extend down parallel with and adjacent to the distributing pipes 47, and their lower ends terminate a 85 slight distance above the tread ring. These plates prevent the ore discharging from the pipes from sliding over the edge of the tread ring, and as the rollers travel upon the ring, the receptacle revolving with it, as will be 90 presently shown, the plates, each of which is in advance of one of the rollers, will level off the ore to a uniform depth over the surface of the tread ring, and thus facilitate the action of the rollers. A conical distributor 95 49, is secured to the shaft 31, above the receptacle 46, and is of less diameter than the said receptacle, and above this distributor is an adjustable, conical feeder 50, which lies over and adjacent to the distributor, and 100 is supported upon rods 51, which pass through the angle bars 14, and are held by nuts 52, which are screwed upon the threaded ends of the rods, and against the angle bars. The under face of the conical feeder 105 is formed with tangential ribs 53, and when the feeder is adjusted to the proper distance relatively to the distributor 49, the ribs work the ore out over the circumferential edge of the distributor, as will presently appear. 110

The apex of the feeder 50 terminates in a hub 54, which surrounds the shaft 31, and is of considerably greater diameter than said shaft, and in this hub is secured the discharge neck of a conical hopper 55, which is supplied from a chute 56. Upon the angle bars 13, is secured a bearing block 57, which surrounds the shaft 31, and this block is formed with a ball race 58, in which is placed anti-friction balls 59, and upon the 115 balls rests the hub 60 of a bevel gear wheel 61, the said hub being also formed with a ball race corresponding to the one in the block 57. The hub 60 is formed with a vertical groove 62, in which fits a spline 63, 120 which is rigidly secured in the upper portion of the shaft 31, and this spline is adapted to slide in the groove 62, as the shaft 31 descends, owing to the wear upon the crushing rollers and the tread ring 19. 125

A shaft 64, is mounted in bearings 65 secured to the upper angle bars 12, and upon this shaft is secured a bevel pinion 66, which meshes with the gear wheel 61, and upon the 5 outer end of the shaft 64 is secured a band pulley 67, which is connected with a source of power.

In operation, the machine is set in motion, and ore or other material which has first 10 been crushed to a degree of fineness suitable for treatment in the herein described machine, is fed from the chute 56, into the hopper 55, and falls upon the distributer 49, which revolves with the shaft 31, and is fed 15 down over the circumferential edge of the said distributer by the conical feeder 50, its ribs 53 preventing clogging of the ore and insuring its discharge from the distributer. The ore falls in a circular sheet into the revolving receptacle 46, and passes out 20 through the distributing pipes 47, upon the tread ring 19, and is prevented from flowing over the edge of the ring by the shields 48, which also level the ore to a uniform depth 25 upon the tread ring, as above stated. The ore falls upon the tread ring in advance of the rollers, and as they travel around the ring, the ore is crushed and pulverized by the said rollers, which are of sufficient 30 weight for the purpose, and discharges over the circumferential edge of the ring and falls upon the conical base ring 1, between the said base ring and the rim 5 of the platform 4, and passes through the apertures 6 35 in the rim 5 and falls upon the disk 39 of the wheel 38, where it is discharged by centrifugal force upon the upper end of the screen 40. The ore passes down over the surface of the revolving screen, which is of 40 a suitable mesh for the purpose required, and the fine material passes through the screen and into the conical chute 43, while the coarse material passes out through the spout 42 at the bottom of the screen, where 45 it is collected and reserved for regrinding. The fine material is led to a separate receptacle by the spout 44, and is ready for concentration or other suitable treatment. The two-part feature of the base 1, the tread 50 ring 19, and the cap 16 facilitate shipping or repairing of the parts, and the hollow shafts which are supplied with oil provide for constantly and automatically supplying the lubricant to the roller and shaft bearings. 55 Moreover, the sliding feature of the shaft 31, within the gear wheel 61, consequent upon the wearing away of the crushing rollers and tread ring, prevents the said gear from getting out of mesh with the pinion 66. 60 Having described the invention, what I claim as new and desire to secure by Letters Patent, is:

1. In an ore dressing machine, a supported base; a frame secured to said base; a gear wheel rotatably mounted upon said

frame; a vertical shaft, one end of which has a sliding engagement with the hub of said gear wheel, but adapted to turn therewith, and means for rotating said gear wheel; lateral shafts secured to said vertical 70 shaft; vertical disk-shaped crushing rollers mounted on said shafts; a horizontal tread ring on said base upon which said rollers are adapted to roll; a circular receptacle supported upon said roller shafts, and adapted 75 to revolve with said shafts and said rollers; a conical distributer secured to the vertical shaft above said receptacle; a conical feed disk adjustably mounted upon said frame relatively to said conical distributer, to form 80 a feed passage between said distributer and said feed disk, said feed disk being provided with a hub which surrounds said vertical shaft loosely; a conical hopper, the lower end of which fits into said hub and which 85 surrounds said shaft; means for feeding ore from said receptacle in advance of the rollers; a casing surrounding said receptacle and said rollers and said base, and provided with an inverted conical chute portion; a 90 conical screen secured to the shaft below said base and arranged to receive the pulverized ore from said tread ring and the chute portion of said casing; a conical chute surrounding said conical screen and attached 95 to said base; and separate discharge spouts at the lower ends of said screen and chute.

2. In an ore dressing machine, a base in the form of an inverted conical band; a platform of less diameter than the upper edge 100 of said base and integrally secured to said base by a rim having a plurality of apertures; a two-part tread ring secured to said base; a vertical shaft extending above and below said base and through the axial center of the same; lateral shafts secured to said vertical shaft, and means for rotating said vertical shaft; crushing rollers having projecting hubs which extend into said bearings, and which are adapted to travel on 105 said two-part tread ring; caps on the outer ends of the lateral shafts, which are adapted to hold said rollers in place; a circular receptacle secured to said bearings and adapted to rotate upon its axis with said rollers; pipes connected to the bottom of said receptacle and adapted to feed ore in advance of said rollers; shields for preventing the ore from said pipes from discharging over the edge of said tread ring and for 110 leveling the ore to a uniform depth on said ring; means for feeding ore to said receptacle; a conical screen on the lower end of said shaft below said base; a disk for receiving the ore as it discharges from the 115 base through the apertures of said platform rim and for discharging said ore by centrifugal force against the upper portion of said screen; and a conical chute surrounding 120 said screen.

3. In an ore dressing machine, a two-part base; a two-part tread ring mounted upon said base, and an upright frame secured to said base; a driven pinion secured to said frame; a gear wheel in mesh with said pinion and a hollow shaft in sliding engagement with the hub of said gear wheel, but adapted to rotate therewith, and an anti-friction bearing for said gear wheel, which is mounted upon said frame; a cross coupling secured at its upper end to the lower end of said shaft; lateral hollow shafts projecting from opposite ends of said cross coupling; bearings secured upon said lateral shafts; rollers having hubs which project into said bearings, said rollers being adapted to travel upon said tread ring; caps secured upon the outer ends of said lateral shafts, which secure said rollers against dis- placement; a bearing in the axial center of 20 said base; a hollow shaft extending from the lower end of said cross coupling through said bearing; a wheel secured upon said shaft below said base, of greater diameter than said base; a disk secured upon the lower side of 25 said wheel, of less diameter than the inner surface of said wheel; a receptacle upon the bearings of said rollers; pipes in the bottom of said receptacle; and means for feeding material in a uniform stream to said receptacle.

In testimony whereof I affix my signature in presence of two witnesses.

HOWARD G. KING.
